UNITED STATES PATENT OFFICE.

CHARLES E. THOMPSON, OF LANSINGBURG, NEW YORK.

DESIGN FOR A BRUSH.

SPECIFICATION forming part of Design No. 17,383, dated June 7, 1887.

Application filed April 25, 1887. Serial No. 236,085. Term of patent 7 years.

To all whom it may concern:

Be it known that I, CHARLES E. THOMPSON, a citizen of the United States, residing at Lansingburg, in the county of Rensselaer and State of New York, have invented and produced a new and original Design for Brushes, of which the following is a specification, reference being had to the accompanying drawings, forming part thereof.

Figure 1 of the drawings is a face plan view of my newly-designed brush. Fig. 2 is a corner view in perspective. Fig. 3 is a similar view to that in Fig. 1, showing the edges of the head-block scalloped. Fig. 4 is an end elevation.

The leading feature of my design consists of three rows of pencils or small brushes arranged in quincunx order upon the face of the head block or plate of the brush in such a manner that the head-bands of the individual pencils appear to be circular elevations raised up from the face of the plate, and the ends of the pencils to project from such elevations.

The facial outline of the plate or brush-head is that of a parallelogram with rounded or tapering ends and corners. This outline may

be straight on the sides and have a long sweeping curve at the ends, or the whole outline may be made up of a succession of short curves forming scallops C, as shown in Fig. 3.

In the drawings, A is the head-block or plate, B B are the projecting ends of the pencils or small brushes, and B' B' their head-bands.

I claim—

The design for a brush hereinafter shown and described, consisting of the facial outline of the brush, the same being that of a parallelogram with rounded corners and ends and scalloped edges, provided with three rows of pencils or small brushes, grouped in quincunx order upon the face of said plate, the ends of said pencils being circular in form and having the appearance of projecting from circular elevations raised from the face of said plate.

In testimony whereof I have hereunto set my hand this 22d day of April, 1887.

CHARLES E. THOMPSON.
